(57) CLAIM

I claim the ornamental design for a jersey, as shown and described.

DESCRIPTION

The patent file contains at least one drawing executed in color. Copies of this patent with color drawing(s) will be provided by the Patent and Trademark Office upon request and payment of the necessary fee.

FIG. 1 is a photographic front view of a jersey, showing my new design;

FIG. 2 is a rear view thereof;

FIG. 3 is a left side view thereof;

FIG. 4 is a right side view thereof;

FIG. 5 is an enlarged front view of a neck region from FIG. 1;

FIG. 6 is an enlarged front, left perspective view of a neck region from FIG. 1; and

FIG. 7 is an enlarged front, right perspective view of a neck region from FIG. 1.

FIG. 8 is a photographic front view of the jersey of FIGS. 1-7 in grayscale;

FIG. 9 is a rear view thereof;

FIG. 10 is a left side view thereof;

FIG. 11 is a right side view thereof;

FIG. 12 is an enlarged front view of a neck region from FIG. 8;

FIG. 13 is an enlarged front, left perspective view of a neck region from FIG. 8; and,

FIG. 14 is an enlarged front, right perspective view of a neck region from FIG. 8.

The broken lines depict features of the jersey that form no part of the claimed design.
